SOCKET MOVING DEVICE

Clarence L. Patterson, Cincinnati, Ohio, assignor
to The International Manufacturing Company,
Cincinnati, Ohio, a corporation of Ohio

Application August 20, 1932, Serial No. 629,584

2 Claims. (Cl. 240—44.25)

This invention relates especially to a device for tilting or moving the bulb of an automobile lamp relatively to the reflector in which it is mounted. Although this idea is not new, broadly speaking, 5 in that the accomplishment has been for the purpose of placing the bulb so that its filament is either in or out of focal position relatively to its mounting reflector, in order to create a change in light beam direction, characteristics, etc., in 10 this and my copending application Serial No. 608,658 there are disclosed the novel ideas of multiple position mechanisms whereby the placing of a lamp bulb in any one of a series of positions relatively to its mounting reflector may be 15 accomplished.

An object of the invention now to be described, is to produce means whereby the movement of a lamp bulb through a series of different stations or stops may be accomplished quickly, accurately, 20 positively, successively, and selectively for the purpose outlined.

A further object is to produce such a means as will move a lamp bulb electrically relatively to a reflector, with a minimum of energy expenditure 25 for current consumption, and in a manner such that the apparatus may be controlled with the greatest of ease and simplicity.

These and other objects are attained in the socket moving device described in the following 30 specification and illustrated in the accompanying drawings, in which:

Fig. 1 is an enlarged elevational view, partially in section such as would be taken on the line 1—1 of Fig. 2, with the reflector entirely removed, 35 showing my improved socket moving device in a desirable form of the invention.

Fig. 2 is an enlarged plan view of the device shown in Fig. 1, a portion of the reflector being shown fragmentally and in section in association 40 therewith.

Fig. 3 is a side elevation of the device shown in Figs. 1 and 2, a portion of the reflector being shown in connection therewith, and the device shown inverted to illustrate how position may be 45 varied without affecting operation.

Fig. 4 is a partial elevation showing associated operative details of my invention, for the purpose of showing the different positions which certain of the parts occupy at different stages of the 50 operation of the device, and for the purpose of disclosing the manner in which the function performed by the device, produces the results which are desired.

Fig. 5 is a perspective view of a detail of the 55 invention I am about to describe, which detail

constitutes an important feature of my invention.

The chosen form of my invention is constructed on and about a frame constituting a sheet metal plate 11 which is fastened to the rear of the reflector 12 with which the device is functioned. 60 This plate is mounted upon the rear of the reflector by means of a flange and threaded collar 13 which lies against the inner finished surface of the reflector, as shown in Figs. 2 and 3. A portion 14 of the plate 11 extends rearwardly and 65 is provided with two extending bearing lugs 15 and 16 for the lamp bulb connector 17, pivotally to mount it, as represented in full and dotted line positions of the socket and bulb, in Fig. 3. In addition to the bearing lugs 15 and 16 there are 70 provided lugs 18 and 19 which extend to opposite sides of the extension 14 in front of lugs 15 and 16, for the purpose of mounting the operating magnets 20 and 21 by means of which the movements functioning the operation of the device, 75 are initiated. The plate 11 is provided further with an extending portion 22 which pivotally mounts a ratchet cam 23 which has oscillating movement for the purpose of creating an upward and downward movement of the lamp socket and 80 its mounted bulb as will be described. This ratchet cam, which is illustrated in detail in Fig. 5, and which is shown in the various figures of the drawings under reference numeral 23, is in the form of a piece having four branches, with 85 the pivot point 24 centrally located, three of the branches 25, 26 and 27 being notched as and for the purpose which will be described, the remaining branch being provided with an eccentric end surface 28 constituting a cam by means of which 90 the socket is caused to move to and from the dotted and full line positions shown in Fig. 3 and also shown somewhat diagrammatically in Fig. 4.

The toothed branch 27 of the ratchet cam is provided with an end turned at right angles to 95 the substantial plane of the cam, for the purpose of placing the teeth in position to be engaged by the detent spring 29 which constitutes a pawl, and which is fastened at points 30 and 31 on the plate 11. Thus, the ratchet cam may be retained 100 in any one of the positions to which it may be moved and which are determined by the number of teeth in the branch 27. Thus, there are three teeth 27a, 27b and 27c, as shown especially in Fig. 5, which will determine the fact that the 105 ratchet cam may be moved to any one of three positions and thereby be retained in any one of these positions by the detent 29, as suggested in Fig. 2. As stops for the movements of the ratchet cam, I have provided stop lugs 27d and 110

27e on branch 27 of the ratchet cam, as shown especially in Figs. 2 and 5. Therefore, in order to correspond with the three teeth 27a, 27b and 27c, I have provided on each of the branches 5 25 and 26, a corresponding number of three teeth each. The teeth 25a, 25b and 25c of branch 25, are adapted to move the ratchet cam counter-clockwise as viewed in Fig. 1, by means of a pawl 32, the connection of which and its operation, 10 being described presently. On branch 26, I have provided a series of three teeth 26a, 26b and 26c, which, through a pawl 33, corresponding to pawl 32, will cause movement of the ratchet cam in a clockwise direction through connection and a 15 functioning which will be described presently.

In order that the socket 17 may be caused to rock upon the bearings 15 and 16, the cam 28 has been provided for moving the socket against the tension of a compression spring 34 which is centered upon a stud 35 in the rearward extension 20 of plate 11 of the socket moving device. Thus, the spring 34 will hold the socket and its bulb in one position, while cam 28 will function to move the socket and bulb against its tension when 25 moved in a counter-clockwise direction as viewed in Fig. 1, and allow the socket to return in response to action of the spring, when the cam is moved in clockwise direction. This, because of the three teeth 27a, 27b and 27c, will take place 30 in three steps.

I will now describe the construction of the electromagnets 20 and 21, the connection of the respective pawls 32 and 33 therewith, and the manner in which operation of these magnets will cause the pawls to function. Each magnet consists of a spool 36 containing a winding 37 which is located within a shell 38 or casing of magnetic material. A partial core 39 is located within the magnet and is provided with a stem 40 by means of which a nut 41 will clamp the magnet assembly 35 to the lugs 18 or 19 to which it is to be fastened. This partial core 39 extends only part way into the magnet spool and is provided with a conical recess 42 into which the coned end of a plunger 43 projects for the purpose of creating a magnetic pull of relatively great force and, at the same 40 time, to be able to move the plunger through a relatively great distance. A pivot 44 at the upper end of the plunger 43, mounts the pawl 32 or 33 45 pivotally, so that when the plunger is drawn down, the pawl also will be drawn downwardly. Each pawl is provided with outwardly extending fingers 45 and 46 which extend into slots 47 and 48 on the casing 38 of the magnet, upward and 50 downward movement of the plunger 43 operating to move pawl 32 or 33, thereby causing their outwardly extending fingers 45 and 46 also to travel in the slots 47 and 48 of the magnet casing 38. Back of the fingers 45 and 46 of each of the pawls 55 is located a coil spring 49 of the conical type, the magnet end of the spring resting on the head of the magnet and the opposite end of the spring extending outwardly through slot 48 and lying against finger 46 of the pawl, whereby, when the plunger 43 is moved into the magnet winding 37, the outwardly extending end of spring 49 will bear against finger 46 of the pawl and thus operate to throw the pawl 32 toward the teeth of ratchet cam branch 25 or 26, whereby engagement of the pawl with the teeth will be accomplished each time the magnet plunger is drawn into the magnet winding 37, in this manner causing the ratchet cam to be moved in a step by step manner, the spring 49 acting to restore the plunger and pawl to extended position after each exci- 60

tation of the magnet. At the upper end of each magnet casing 38 is an inner circumferential groove into which fits a wire ring 51 which limits the upward movement of the pawl by reason of its fingers 45 and 46 moving into engagement 80 with the ring at the point where the ring crosses the slots 47 and 48 to close the upper end, as shown in Fig. 1. This position and relationship also is shown in Fig. 4, which figure shows, in dotted lines, the manner in which the end 50 of spring 49 functions to throw the pawl into engagement with the tooth of the toothed end 25 or 26 of the ratchet cam for the purpose of moving the bulb socket. 85

Limitation of movement of the ratchet cam to 90 one side or the other of its swing, is accomplished by providing lugs 52 and 53 on each side of frame plate 11, whereby the turned over ends of branch 27 will be brought to engage its stops 27d and 27e with these lugs 52 and 53 at each end of the swing 95 of the ratchet cam. Therefore, after each of the pawls 32 and 33 have operated to move all three of the teeth of each set, these pawls cannot cause any further movement of the ratchet cam because the cam is held positively against further 100 movement.

The operation of the device I have just described is simple and, from the description which has been given above, its functioning may appear to be obvious. However, in order that there may 105 be no mistake as to the exact performance of the mechanism, the following description is given. First of all, let it be assumed that the normal position of the lamp bulb is that in which the filament occupies the focal region of the reflector. 110 Such a position affords a desirable light for purposes of driving through the country districts where the only source of illumination comes from the vehicle headlamps. This position of the bulb filament affords a penetrating beam which projects far ahead of the vehicle and illuminates the road surface desirably, as well as the objects to either side of the road and adjacent thereto. Such a beam is not desirable for purposes of city driving where the streets are illuminated and 115 where the glare of the car's headlamps is objectionable for various reasons. Therefore, in order to overcome these objections, movement of the lamp bulb to a position out of the focal region of the reflector, is desirable. To illustrate these two relative positions, I have shown, 120 in Fig. 3 of the drawings, the dotted line non-focal position and the full line focal position. In dotted lines in Fig. 4, I have shown the focal position of the lamp bulb connector by means of 125 the circle 54 and the dotted position 55 of the cam 28, in which the cam pushes the connector against the tension of spring 34. Obviously, when it is desired that the connector shall be moved to a position where the lamp bulb occupies the dotted 130 line position shown in Fig. 3, which is the out of focal position, all that is necessary is to rotate the ratchet cam upon its pivot 24, to the full line position as shown in Figs. 1 and 4, thereby permitting spring 34 to move the lamp bulb socket 135 17 in order that it may pivot and move the lamp bulb to the dotted line out of focal position shown in Fig. 3. Therefore, all that remains to accomplish these two movements is to function the operation of the two magnets 20 and 21 so that the 140 two pawls 32 and 33 will operate as now described. 145

Assuming the position of the ratchet cam to be as shown in Figs. 1 and 4, the spring 49 in each of the magnet structures 20 and 21, being extended, will cause pressure upon the pawls 32 150

and 33, whereby the plungers 43 will be lifted and the pawls 32 and 33 held in position such as shown in Figs. 1 and 4. In addition to this, the end 50 of the spring 49, extending through slot 5 in the casing 38 of the magnet structure, will bear upon finger 46 of the pawl and tend to press the pawl toward the teeth of the ratchet cam. However, the wire ring 51 which retains the pawl and its attached plunger 43 in position, will come into action upon the plunger 43 having moved the pawl to its position away from the ratchet teeth, whereby the fingers 45 and 46 will engage the wire ring and hold the pawl away from the teeth, as shown in full lines in Figs. 1 and 4. However, when the coil 37 of the magnet is energized, the plunger 43 will be drawn into the winding, thereby drawing pawl 32 and disengaging fingers 45 and 46 from the wire ring 51, whereupon the end 50 of spring 49 will exert a yielding pressure upon finger 46 and operate to move pawl 32 into engagement with the tooth 25a, as shown in Fig. 4 in dotted lines. Continued movement of the plunger 43, until it engages core 39, will cause the tooth 25a to be pulled, thereby moving the ratchet cam about its pivot 24 the distance equal to the space between teeth. This will occasion the cam surface 28 sliding over the socket and will result in movement of the socket in a slightly depressed position, whereby the lamp bulb filament will approach the focal center of the reflector. Upon releasing the plunger 43 and pawl 32, spring 49 will move them so that the pawl may be caused to engage tooth 25b upon reenergizing the magnet coil 37, thus resulting in a further movement of the ratchet cam to produce an additional depression of the socket, thus bringing the lamp bulb filament still closer to the focal center. Deenergizing magnet coil 37 will again result in the plunger 43 and pawl 32 being allowed to move under pressure of spring 49, so that they will be in position for the pawl to engage tooth 25c, re-energization of the magnet again causing pawl 32 to draw upon the ratchet cam and thereby depress the socket until the lamp bulb filament has been moved to focal region position relatively to the reflector. It will be observed that spring latch 29 will function to engage each of the teeth 27a, 27b and 27c successively in the function of retaining the ratchet cam in its positions as determined by the operation of the motor mechanism represented by the magnet 20 and pawl 32.

Now, motor or magnet 20 having been functioned to cause pawl 32 to operate the ratchet cam 23 to cause the bulb socket to be moved to focal position, such as shown in dotted lines in Fig. 3, the motor or magnet 21 is functioned to produce an elevation of the bulb in order that the light beam may be depressed for ordinary driving purposes. This, through pawl 33 operating upon teeth 26a, 26b and 26c, causes the ratchet cam to be moved to a position such as shown in Fig. 1, in which cam face 28 has allowed the

socket to be lifted by spring 34, and, in doing so, causes the movement to take place in three steps, thereby functioning the placing of the light bulb so as to afford three types of light beam for illumination purposes. Again, it is obvious that the latch 29 functions to retain the bulb and its mounting socket in any one of the three positions.

In view of the foregoing, it is obvious that, at any stage, the movement of the ratchet cam may be stopped and reversed, thereby occasioning a return to one position or another with but the mere use of a simple switch in circuit with each magnet motor, or a single switch having double contact construction.

Having thus described my invention what I claim is:

1. A socket moving device comprising in combination with a reflector, a lamp bulb socket, means to mount the socket for rocking movement to bring a bulb therein into and out of focal region placement relatively to the reflector, a cam pivotally mounted adjacent to and in engagement with the socket to move it in one direction and permit its movement in the opposite direction, yielding means tensioned by the socket movement in the first mentioned direction and causing socket movement in the second mentioned direction, a motor to move the cam in one of said directions, a motor to move the cam in the other of said directions, a separate ratchet mechanism associating the cam with each motor, and independent means on each motor automatically disassociating the ratchet mechanism associated therewith upon reaching one limit of movement of said mechanism.

2. A socket moving device comprising in combination with a reflector, a lamp bulb socket, means to mount the socket for rocking movement to bring the bulb therein into and out of focal region placement relatively to the reflector, a cam pivotally mounted adjacent to and in engagement with the socket to move it in one direction and permit its movement in the opposite direction, yielding means tensioned by the socket movement in the first mentioned direction and causing socket movement in the second mentioned direction, a motor to move the cam in one of said directions, a motor to move the cam in the other of said directions, a separate ratchet mechanism associating the cam with each motor, independent means on each motor automatically disassociating the ratchet mechanism associated therewith upon reaching a chosen limit of movement of said mechanism, said two independent means being adapted simultaneously to disassociate the ratchet mechanisms from the motors, whereby the cam may be disconnected from both motors at the same time, and a lock operating automatically to retain said cam in any of the ratchet adjusted positions upon disassociation of the ratchet mechanisms therewith.

CLARENCE L. PATTERSON.
